FAN BLADE

Arthur L. Wood, Indio, Calif.

Application August 20, 1936, Serial No. 97,060

1 Claim. (Cl. 170—159)

This invention relates to a fan blade primarily intended for high speed heavy duty motors where a large volume of air with a minimum amount of noise is required, such as for ventilators or air coolers, although it is to be understood that the improvements are not so limited as they may be applied even to an airplane propeller.

It is particularly aimed to provide such a construction as will be practically noiseless, as the blades thereof are provided with a sloping leading edge with a graduated pickup and rounded rear edge and with a large center to prevent recirculation.

The more specific objects and advantages will become apparent from a consideration of the description following taken in connection with accompanying drawing illustrating an operative embodiment.

In said drawing:—

20 Figure 1 is a view of the fan in plan;

Figure 2 is a cross sectional view taken on the line 2—2 of Figure 1, and

Figure 3 is cross sectional detail taken on the line 3—3 of Figure 1.

25 Referring specifically to the drawing wherein like reference characters designate like or similar parts, the fan constituting my invention is generally of S-shape as shown at 10. It is in a single piece of sheet metal, adapted to be stamped therefrom into the novel shape and it is pivoted or otherwise secured to an attaching hub 11 as at 12, registering openings being provided through the hub and blade as at 13 and 14, and a set screw 15 preferably being carried by the hub to engage 30 the shaft which drives the fan.

35 In accordance with the invention, any desired number of blades 16, for instance two as shown, may be provided on the fan, and such blades

from opposite sides have a sloping leading edge portion at 17, merging into a graduated pickup portion at 18, and in turn merging into a rounded rear or curved edge portion 19 (Figures 1 and 2). In addition, the central portion 20 of the 5 fan is relatively large so as to prevent recirculation of the air disturbed by the blades 16.

As a result of the construction described, the fan will stir a large volume of air with a minimum amount of noise and the relatively large 10 center will stop any back flow so as to force all of the air forward under the action of the blades. The novel action is particularly apparent in a one-fourth horse-power motor with a speed of 15 1750 revolutions per minute.

While the device is primarily adapted for use in high speed heavy duty motors where a large volume of air with a minimum amount of noise is required, as in ventilators and air coolers, the 20 principles may also be applied to advantage in airplane propellers. In such instance, the curved edge 19 would be somewhat flexible so as to make the fan blades self-adjusting for high and low altitudes.

25 Various changes may be resorted to within the spirit and scope of the invention.

I claim as my invention:—

A fan blade structure generally of S-shape in plan, providing fan blades at the two extremities thereof and a relatively large portion between the blades constructed and arranged to function for preventing recirculation of air, each blade having a sloping leading edge portion extending inwardly beyond the rear edge portions, 30 respectively, said rear edge portions being rounded, substantially as described.

ARTHUR L. WOOD.
